CONTAINER

Robert Nyden, Manhasset, N. Y., assignor to
American Can Company, New York, N. Y., a
corporation of New Jersey

Application August 21, 1941, Serial No. 407,834

4 Claims. (Cl. 220—43)

This invention relates in general to containers which are closed by means of a friction plug and more particularly to a novel container top and friction plug construction which is adapted for easy opening in connection with a variety of different shapes and sizes of containers.

An object of the invention is the provision of a novel improved friction plug closure for friction top containers which is adapted to tightly close the friction ring opening of such containers, thereby providing a tight seal which may be readily disengaged from its tight frictional engagement with the friction ring without any special opening tool, by the exertion of pressure upon a portion of the friction plug, which may be mere finger pressure.

Another object of the invention is the provision of such a friction plug construction which has a novel fulcrum projection formed integrally with the friction plug, which projection is adapted to rock upon the friction ring, when a portion of the plug is depressed, thereby raising another portion of the plug to loosen and then remove the plug from its seat.

Still another object of the invention is the provision of such a friction top construction having the enumerated advantages, which may be economically produced by simple die operations on readily available equipment and materials.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a cylindrical type of friction top container showing one exemplary embodiment of the present invention.

Fig. 2 is an enlarged vertical sectional view of the container top of Fig. 1, taken along lines 2—2 and showing the friction plug in sealing position.

Fig. 3 is a view similar to Fig. 2 and showing the friction plug partially removed, i. e., depressed at one end and raised at the other, with the fulcrum projection rocking on the friction ring, and

Fig. 4 is a perspective view of the top portion of an oblong container, illustrating application of the invention to containers other than of cylindrical shape.

Referring in more detail to the preferred embodiment of the invention exemplified in the

drawing, Figs. 1 to 3 illustrate a fibre body 11 which is closed at the bottom by means of a sheet metal end 12 permanently crimped thereto. To the top marginal edge of the body 11 is crimped a sheet metal end or annular friction ring 13 in a permanent end joint 14. Inwardly of the joint 14 the ring 13 comprises a vertical wall which closely hugs the inner surface of the body 11 until it merges into a horizontal countersink or panel 15, which preferably includes an upwardly raised inclined wall to provide an annular bearing portion or ridge 16. Thence the metal of the ring is bent downwardly at an acute angle to said upwardly raised wall to provide a depending friction seat wall 17, which in turn is bent outwardly and upwardly, terminating in a curved flange or curl 18. A dish-shaped friction plug closure element or shell 19 is adapted to fit tightly within the filling and pouring opening defined by the depending wall 17 to provide a top seal.

The friction plug 19, in use with a cylindrical container, is preferably a one piece cylindrical shell, stamped or rolled out of sheet metal and comprises a suitably panelled closed top wall 21, which merges into a curved depending friction seat wall 22. The metal of the plug shell between the top panel 21 and the friction wall 22 is shaped into an outwardly projecting segmental bead 23 at one peripheral portion of the plug. A short distance below the top wall 21 and at a point diametrically opposite the bead 23, the metal of the depending wall 22 is projected outwardly into a segmental stop bead 24, which limits the inward movement of the plug and determines its correct closing position. Substantially centrally between the beads 23 and 24 and at diametrically opposed points the metal of the depending wall 22 is again projected outwardly, preferably at the level of the stop bead 24, into two opposed fulcrum or rocker beads 25. The beads 24 and 25 thus divide the depending wall 22 into curved annular sections, i. e., into a short curved annular wall section 26 located above the top of these beads and into a longer curved annular wall section 27 which is located below the bottom of these beads. The wall section 27 provides the friction seat wall of the plug and terminates at the bottom in a raw edge 28. The metal of the wall section 27 is chamfered or cut away at 29 on that side of the plug which contains the bead 23 to provide clearance space when pressure is exerted on the plug at the bead 23 to rock the plug into open position. The provision of this chamfer or cut away is desirable when

the container is filled with solid or semi-solid material, for instance cigarettes 31, as illustrated in Figs. 2 and 3, but may be eliminated in case of a liquid or powdery product which is readily displaced.

In case the container is used for dry products, it may be desirable to provide an auxiliary cover 32 over the contents. This may extend over the entire top surface of the contents or, as shown in Figs. 2 and 3, it may coincide as to area with the size of the filling opening, permitting insertion therethru. This cover may be a fibre or paper disc or metal foil or other suitable material and may provide a top surface for such printed matter as advertisements or directions for use of the contents.

As seen in Fig. 4 the present invention may be applied to oblong containers or any other practical shape of container and such containers may be used for holding and dispensing a variety of products, the cigarettes 31 shown in Figs. 2 and 3 being merely illustrative of the possible wide use of such an easily opened container.

Fig. 2 shows the friction plug 19 in its correct closing position. Note that in such position the stop bead 24 and the rocker beads 25 rest upon the annular ridge 16 and the upper portion of the annular wall section 27 frictionally engages the friction seat wall 17 of the ring 13 and that the manually depressible bead 23 is spaced vertically away from the ridge 16.

When it is desired to open the container, to expose or remove the contents, pressure exerted against the edge of top panel 21 at the locality of the bead 23 (which may be finger pressure) will depress that portion of the plug and raise the opposite portion of the plug, causing the wall section 27 of the plug to disengage itself from the friction seat wall 17 of the ring, thereby initially loosening the plug as an entirety from its sealing contact with the ring for subsequent easy and complete removal. In other words, a lever or rocking movement of the plug 19 upon the ring 13 takes place and is accomplished by the opposed beads 25 of the plug rocking or fulcruming on the ridge 16 of the ring. The curvature of the wall sections 26 and 27 of the plug assist in clearing the depending wall 17 of the ring. Fig. 3 shows the relative position of plug and ring after such fulcrum or rocking movement.

In some cases the stop bead 24 may be omitted or may be replaced by a second pressure bead or projection 23, in which case the rocker beads 25 would also function as stop beads limiting the relative telescoping movement between plug and ring. It is conceivable that both stop bead 24 and pressure bead 23 may be omitted in the event that it is not necessary or desirable to limit the inward movement of that portion of the plug upon which pressure is exerted.

It will be understood of course that while the ring 13 and plug 19 have been illustrated and described as being made of sheet metal, either or both of these members may be made of any other suitable material. For instance, the plug would function in a similar manner if it were made of plastic. Also, of course, the container body, instead of being made of fibre, as illustrated and described might be made of sheet metal.

It is thought that the invention and many of its attendant advantages will be understood from the foregoing description, and it will be apparent that various changes may be made in the form, construction and arrangement of the parts without departing from the spirit and scope of the in-

vention or sacrificing all of its material advantages, the form hereinbefore described being merely a preferred embodiment thereof.

I claim:

5. 1. A friction plug container, comprising in combination, a container body, a friction ring secured to said body in a joint and having a depending friction seat wall defining a pouring and dispensing opening, a friction plug for closing said opening, said plug having an outwardly curved peripheral friction seat wall adapted to sealingly engage the friction seat wall of said ring when said plug is disposed flatly thereagainst, said plug also having a pair of horizontally elongated fulcrum projections located at 15 diametrically opposed peripheral points of the plug and having a flat bearing engagement against said ring to maintain the plug in horizontal sealing position, whereby the application of inward pressure upon said plug at a point substantially centrally between said projections rocks the plug on said ring at one end of said elongated fulcrum projections to raise the opposite end of the plug, and release the frictional engagement between plug and ring, the outwardly curved friction seat wall of said plug permitting the described rocking movement of the plug without binding against the ring.

2. A friction plug container, comprising in combination, a container body, a friction ring secured to said body in a joint and having a depending friction seat wall defining a pouring and dispensing opening, a friction plug for closing said opening, said plug having an outwardly curved peripheral friction seat wall adapted to sealingly engage the friction seat wall of said ring when said plug is disposed flatly thereagainst, said plug having a horizontally elongated fulcrum projection bearing flatwise against said ring when the plug is in horizontal sealing position, and a pressure bead in said friction plug spaced horizontally and vertically from said fulcrum bead, whereby application of inward pressure upon said plug at said pressure bead the plug is rocked on said ring at one end of said horizontally elongated fulcrum projection to raise the opposite end of the plug and release the frictional engagement between plug and ring, the outwardly curved friction seat wall of said plug 40 permitting the described rocking movement of the plug without binding against the ring.

3. A friction plug container, comprising in combination, a container body, a friction ring secured to said body in a joint and having a depending friction seat wall defining a pouring and dispensing opening, a friction plug for closing said opening, said plug having an outwardly curved peripheral friction seat wall adapted to sealingly engage the friction seat wall of said ring, said plug also having a horizontally elongated fulcrum projection bearing flatwise against said friction ring when said plug is in horizontal sealing position, a stop bead at one peripheral point of said plug to limit the inward engagement between plug and ring and a pressure bead at a point diametrically opposite to said stop bead and spaced vertically therefrom, whereby the application of inward pressure upon said plug at said pressure bead rocks the plug on said ring at one end of said horizontally elongated fulcrum projection to raise the opposite end of said plug and loosen the frictional engagement between plug and ring, the outwardly curved friction seat wall of said plug permitting the described rock-

ing movement of the plug without binding against the ring.

4. A friction plug container, comprising in combination, a container body, a friction ring secured to said body in a joint and having an up-standing substantially horizontal bearing portion and a depending friction seat wall defining a pouring and dispensing opening, a dish shaped friction plug for closing said opening, said plug having an outwardly curved peripheral friction seat wall adapted to sealingly engage the friction seat wall of said ring, said plug also having a pair of diametrically opposed horizontally elongated fulcrum projections in said friction seat wall between its top and bottom edges for bear-

ing flatwise against diametrically opposed portions of said ring when said plug is in horizontal sealing position, and a pressure bead in said friction plug spaced horizontally and vertically from said fulcrum bead, whereby the application of inward pressure upon said plug at said pressure bead rocks the plug at diametrically opposed portions of said ring at adjacent ends of said horizontally elongated fulcrum projections to raise the opposite end of the plug and release the frictional engagement between plug and ring, the outwardly curved friction seat wall of said plug permitting the described rocking movement of the plug without binding against the ring.
